UNITED STATES PATENT OFFICE

JAMES M. COBURN, OF KANSAS CITY, MISSOURI, ASSIGNOR TO PLANE-SPEAKER CORPORATION, OF NEW YORK, N. Y., A CORPORATION OF DELAWARE

AEROPLANE PHONOGRAPH REPRODUCER

Application filed September 7, 1927. Serial No. 218,012.

This invention relates to aeroplanes, balloons, dirigibles, and other aerial navigating means, which will herein be designated generally as aeroplanes, and it has to do particularly with means for reproducing and amplifying messages to be broadcast therefrom.

The general object of this invention is to provide means for broadcasting from an aeroplane, by which extraneous noises from the motor, propeller or other sources will be substantially excluded from the amplifying system, thereby removing one cause of overloading of the amplifier and distortion of the sound produced.

15 An object is to make use of phonographic reproducing means for supplying impulses to an amplifying system carried by an aeroplane, and to construct the reproducing means so that it may be adjusted so as not to be affected by movements of the aeroplane.

A further object is to provide a sturdy, readily constructed unit for use with the phonographic reproducer which affords positive and non-varying operation thereof independent of changes in gravity, centrifugal, 25 centripetal, or other forces exerted during operation of the aeroplane, whereby normal and uniform reproduction is made possible.

Loud speakers and amplifying units have 30 been heretofore provided on aeroplanes, for the purpose of broadcasting messages, or for advertising purposes. These have made use of microphones into which the announcer spoke; and while they have attained considerable success, certain disadvantages were 35 inherent in them. Among these are chiefly the overloading of the amplifying system by the noises of the motor and propeller, and distortion of the sound produced. The present invention provides means for overcoming 40 these disadvantages, and also makes it possible to use records prepared in advance, either of an advertising nature, or comprising speeches, news, music or other desired material, whereby the record is reproduced 45 faithfully, and with no delays such as may occur in oral broadcasting.

One embodiment of the invention is illustrated in the accompanying drawings, of 50 which Fig. 1 represents a plan view of the

reproducing unit; Fig. 2 a side elevation of the device shown in Fig. 1; Fig. 3 a side elevation of the coupling shown in Fig. 2; Fig. 4 a view, partly in section, of the reproducer and carriage taken on line 55 IV-IV of Fig. 2; and Figs. 5 and 6 schematic representations of two means of converting the mechanical impulses produced by the reproducer to electrical impulses capable of successful treatment in the amplifier. 60

In adapting a phonograph reproducer for use in an aeroplane, the weight of the reproducer and associated mechanism creates special problems because of the inertia forces 65 produced in operation of the craft. For example, if the aeroplane suddenly goes up or down the needle pressure increases or decreases, producing a variation in the impulses 70 conveyed to the reproducer.

Also, side movements of the aeroplane, as in banking, set up centrifugal or similar forces which will tend to press the needle against one side of the grooves, which will vary the impulses set up in the needle, and the side pressure may even become great 75 enough to slow up the record, or to force the needle out of a groove.

Special features of the invention comprise the use with an aeroplane equipped with audio broadcasting apparatus, of a phonograph reproducer pivoted horizontally about its center of gravity and adapted to be resiliently urged vertically against the record to produce a uniform pressure regardless of movements 80 of the aeroplane. In order further to create uniform operation unaffected by changes in direction or speed of the aeroplane, a special frame is provided on which the reproducer is rigidly supported and driven uniformly over 85 the record. The reproducer is designed to convert the impulses received from the record to electrical impulses, so that only the desired impulses are supplied to an amplifying system carried by the aeroplane. 90

Referring to the drawings, the frame mechanism comprises a reproducer head 1, pivotally mounted on a screw-driven carriage 2, which is supported by and driven on a pair of rails 3 and 3a by means of a fixed screw 4. 95 100

The rails are rigidly secured by nuts 5 on to frame members 6 and 6a seating on base plates 7 and 7a, secured to angles 8 in such a manner as to be rigidly supported. The supporting frame thus formed is secured at one end to the base plates by hinges 9, and provided at the other end with latches 10, engaging notches formed in the base, so that end movement is prevented and the supporting frame 5 can be raised when desired. Side movement of the frame is prevented by pins 11 and 11a provided in the base plates and adapted to engage corresponding holes in the end supports. Intermediate the rails and rotatably supported in the end supports is a screw member 4, driven by a bevel gear 12 mounted thereon and secured thereto by a pin or screw 12a. Gear 12 meshes with and is actuated by a bevel pinion gear 13, rotatably supported by 10 a cross brace 14 mounted in fixed position on the rails. The shaft-driving gear 13 is operatively connected to the spindle 15 of a phonograph turntable 16 through a coupling 17. As shown in Figs. 2 and 3 this coupling is 15 counter-bored to receive the spindle, and a pin 18 is horizontally disposed in the center of the bore, to engage a slot 19 cut in the spindle, thus permitting easy disengagement of the coupling when the supporting frame is raised 20 on hinges 9.

A special feature of the invention comprises mounting the reproducer head so as to be unaffected by any change in the inertia forces. This is accomplished by the horizontal pivotal support shown in Figs. 2 and 4. The reproducer head 1 is constructed to be supported on horizontal pivots 20 and 20a whose axis passes through its center of gravity, and which are held in adjustable bearing 35 screws 21 and 21a, accurately threaded in a fork suspension member 22, the outer ends of the screws being secured by bolts 23 and 23a. Suspension member 22 is secured to carriage 2 by a bolt 24, appropriate nuts and 40 washers or spacing members being used. In order to cause the needle 25 to exert a constant pressure on a record placed therebelow, a spring tension device is employed, which, acting with the torqueless pivoting creates a constant pressure regardless of change in the upward or downward forces. This device comprises a pin 26, adapted to bear on the needle end of the reproducer head. Interposed between pin 26 and a screw 27 is a spring 28, 45 the tension of which can be varied by varying the setting of the screw, and which for any particular setting exerts a constant thrust on the pin, pressing the needle with constant pressure into the grooves in the record, the pressure not being varied by movements in a vertical plane.

The reproducer may be adapted for use in audio amplification in a number of ways, two of which are diagrammatically shown 50 in Figs. 5 and 6. In general these methods

depend upon the production of electrical impulses varying in intensity with the vibrations of the needle, caused by the impressions in the record. In Fig. 5 the needle 25a follows the grooves in a record mounted on and rotated by turntable 16a. Operatively connected with the needle 25a and adapted to respond to the slight variations in impulses created in the needle is a vibration transmitting device 30, adapted to vary the pressure on a diaphragm 31 mounted in a resistance box 32. This box is filled with granular carbon, and connected with it is a pair of wires 33 and 34, and battery 35. This device is in principle substantially that of the ordinary telephone transmitter, and requires no extended description other than to state that the resistance to the electrical flow of the battery current through the graphite varies with the pressure applied thereto, and consequently variable electrical impulses are created in response to the varying pressures of the needle, which are conveyed to an amplifying system, not shown, and there converted to audio-frequency and amplified as may be desired.

Fig. 6 shows a modification, in which needle 25b is mounted for axial movement between a pair of magnets 36 and 37, and surrounding it is a helix 38 electrically connected to lead wires 39 and 40, a battery 41 being cut into the circuit. Variations of the record groove cause the needle to move in and out of the magnet fields within the helix, thus varying the currents in the electrical circuit in such manner that impulses are set up which when passed through a suitable amplifying system, as before, reproduce the sounds recorded on the record.

To operate this device, latches 10 are released, permitting the framework, drive mechanism and reproducer to be raised, when a record is placed on the turntable, and then the mechanism is replaced and locked with the latches. The reproducer having been previously set to engage the first groove in the record, as by manually reversing gear 11 while the frame is raised, the mechanism operating spindle 15 may be started, causing the record to revolve, and simultaneously actuating gear 11, and screw 4. This causes the reproducer carriage to move over the record, the gear ratio and pitch of the screw being selected to drive the reproducer at the proper rate, i. e. to move the carriage the width of one groove for each revolution of the record. During this operation the impressions in the record will create vibrational movements of the needle, which in turn are converted to electrical impulses and amplified and the speech, music, advertising or other material on the record transmitted from a suitable loud speaker system carried by the aeroplane.

The use of this principle of reproduction 130

permits broadcasting with none of the interference normally created by the aeroplane itself, inasmuch as no sounds are transmitted to the amplifier, which receives only the positively produced impulses from the record. Furthermore, true reproduction is assured, since the reproducer is rigidly mounted to prevent any lateral movement created by banking or side components of the aeroplane operation, and because the pivoting about the center of gravity and spring tension device insure no variation in needle pressure, and the needle is thus unaffected by inertia forces produced by changes of operation or speed in any direction.

I claim:

1. A reproducing mechanism for use with an aeroplane audio broadcasting apparatus adapted to deliver thereto only those impulses which it is desired to broadcast and whose operation is not affected by movements of the aeroplane, comprising a supporting frame, a power-actuated screw mounted therein, phonograph reproducing mechanism and reproducer-supporting means coacting with said frame to uniformly move the reproducer over a record while maintaining constant needle pressure irrespective of movements of the aeroplane.

2. A reproducing mechanism for use with an aeroplane broadcasting apparatus including a power amplifier, adapted to deliver to the amplifier only those impulses which it is desired to broadcast and which is not affected by movements of the aeroplane, comprising a supporting frame, a power-actuated screw mounted therein, a carriage mounted on said frame and actuated by said screw, phonograph reproducing mechanism mounted pivotally about its center of gravity on said carriage and operatively connected to the amplifier, phonograph turntable mechanism, and means associated with said turntable mechanism for actuating said screw positively to move the carriage and reproducer progressively over a record.

3. A reproducing mechanism for use with an aeroplane broadcasting apparatus including a power amplifier, adapted to deliver to the amplifier only those impulses which it is desired to broadcast and which is not affected by movements of the aeroplane, comprising a supporting frame, a power-actuated screw mounted therein, a carriage mounted thereon and actuated by said screw, phonograph reproducing mechanism pivotally connected about its center of gravity to said carriage, phonograph turntable mechanism, gears associated with said turntable mechanism and said screw to move the carriage and reproducer progressively over a record, and means associated with said reproducer to convert the impulses created therein by the impressions on the record to corresponding

electric impulses, and to transmit them to the amplifier.

4. A reproducing mechanism for use with an aeroplane broadcasting apparatus including a power amplifier, adapted to deliver to the amplifier only those impulses which it is desired to broadcast and which is not affected by movements of the aeroplane, comprising a supporting frame, a power-actuated screw mounted therein, a carriage mounted thereon and actuated by said screw, phonograph reproducing mechanism pivotally connected about its center of gravity to said carriage, phonograph turntable mechanism, adjustable means cooperating between the carriage and reproducer to uniformly and constantly press the reproducer needle on a record, and means associated with said reproducer to connect the impulses created therein by the impressions on the record to corresponding electric impulses, and to transmit them to the amplifier.

In testimony whereof, I sign my name.

JAMES M. COBURN.
